Attorney

UNITED STATES PATENT OFFICE.

ARTHUR K. TAYLOR, OF BALTIMORE, MARYLAND, ASSIGNOR TO UNDERWOOD TYPE-WRITER COMPANY, OF NEW YORK, N. Y., A CORPORATION OF DELAWARE.

TYPEWRITING MACHINE.

1,409,619.

Specification of Letters Patent. Patented Mar. 14, 1922.

Application filed August 9, 1919. Serial No. 316,461.

To all whom it may concern:

Be it known that I, ARTHUR K. TAYLOR, a citizen of the United States, residing in Baltimore, in the county of Baltimore and State of Maryland, have invented certain new and useful Improvements in Typewriting Machines, of which the following is a specification.

This invention relates to round-platen typewriting machines, and is herein disclosed as applied to an Underwood standard typewriting machine.

In round-platen typewriting machines, the lack of a line-indicator, to indicate the numbers of the lines on a sheet as they are successively written, is often a matter of considerable annoyance, especially when nearing the bottom of a sheet. Such an indicator, according to the present invention, may be provided to indicate the number of lines intervening between the line written on at the moment and the bottom of the work-sheet. For this purpose, there may be provided a scale, which is numbered in the direction of the rotation of the platen, with the result that if set upon writing the first line to indicate by a pointer the number of lines which can be written upon the work-sheet, the numbers upon the scale may always indicate by the pointer during the writing the number of lines remaining to be written. The scale may also be correspondingly numbered in the opposite direction, to indicate at the same time the number of lines which have been written.

The device may take the form of a surface adapted to turn with the platen, and capable of receiving a pencil or other mark, so that if such a mark is made at any point the typist may readily bring the platen to the same point again by rotating it until said mark comes to the pointer. This surface may comprise the scale aforesaid.

In order to enable the scale to be readily adjustable to conform to the position of the work-sheet inserted around the platen, the scale may be in the form of a ring, which is adapted to be rotated upon the axle of the platen. In order to detain the ring at the position in the circumference of the platen at which it is set, its mounting may comprise a channel in which is a suitable form of retaining device.

Other features and advantages will hereinafter appear.

In the accompanying drawings, Figure 1 is a perspective view of parts of an Underwood typewriting machine carriage, showing the present invention as applied thereto.

Figure 2 is a front view of the same, partly in section.

The Underwood typewriter carriage 1 comprises the platen frame 2, having ends 3 and 4 connected by the usual rear paper-table 5, which is adapted to guide the work-sheets from the rear up in front of the platen 6, to the printing point opposite the type-bar diagrammatically shown at 7. In order to rotate the platen, the usual line-space handle 8 may actuate the usual line-space slide 9, to rotate the platen by the line-space wheel 10, the platen being journaled in the ends 3 and 4. When a work-sheet is inserted around the platen in this way, its leading edge may be aligned against the usual wing-scales 12, on each side of the usual type-guide (not shown).

To enable the platen to be rotated independently of the line-space lever 8, a finger-wheel 13 may be held fast to the axle 14 of the platen by a hub 15. The finger-wheel 13 at the right-hand end of the platen is herein illustrated as comprising a smooth periphery 16, upon which a ring 17 is adapted to be rotated, said ring comprising on its outer surface division lines 18, forming a scale which is adapted to be read against the pointer 19 conveniently situated for the typist to read and fast to the top 20 of the end plate 4.

There are thirty-three of the lines 18 spaced at equal distances apart, corresponding to the thirty-three teeth of the usual line-space wheel 10, with the result that if the first line 18 is properly set at the pointer 19, the usual detent (not shown) will so hold the platen that every other line upon the ring 17 will fall at the pointer as the platen is rotated. Since the platen of the Underwood typewriter carriage is usually approximately $5\frac{1}{2}$ inches in circumference, and work-sheets frequently run about 13 inches in length, the ring 17 is shown as divided into three columns 21, 22 and 23, the lines 18 in all the columns coinciding, and in one of the columns (advantageously the left-hand one) the lines are numbered from "1" up to "33" in black, so that numerals from "1" up run successively in column 21 in the direction 110

of rotation of the platen. The column 22 immediately to the right is correspondingly numbered from "34" to "66," and the column 23 to the right of that is numbered from "67" 5 to "99." Obviously, when one, two, three or four inches of work-sheet stand above the wing-scales, the number of lines written is to be read from the left-hand column 21 containing the smallest numbers. When an intermediate number of lines (more than 10 thirty-three) has been written, the number is to be read from column 22. When the end 15 of a long work-sheet is being reached, the number of lines written is obviously to be read from column 23. Thus, by an inspection of the columns 21, 22 and 23, the typist will instantly know how many lines have been written, since the length of the work-sheet above the wing-scales 12 is easily recognized.

In order to permit the typist to read in a similar manner the number of lines which may be written upon a work-sheet before the bottom is reached, there are also shown red 25 numerals in the columns 21, 22 and 23. It has been found preferable to place the red numeral "1" with the black numeral "99," the red numeral "2" with the black numeral "98," and so forth. This enables the typist, 30 knowing from experience or from memoranda the length of the work-sheet used, to rotate the ring 17 to bring the appropriate red numeral to the pointer 19, when a work-sheet of a given length has its leading edge 35 at the wing-scales 12. Then during the advance of the work-sheet the typist can read directly from the red digits in column 21, 22, or 23, as the case may be, the number of lines which can still be accommodated upon the 40 work-sheet.

I have found that where the scale-carrying ring 17 and the finger-wheel bearing surface 16 are of iron or steel, a piece of ordinary soft eraser, barely projecting above a channel $\frac{1}{4}$ of an inch wide in the periphery 16 (which thus forms a channeled ring), will serve as an admirable detent for frictionally detaining the ring 17 wherever it is set. For a ring two inches in diameter, a piece of rubber having a bearing surface of one inch upon the ring appears satisfactory.

In order to save the typist the need of reading the numerals upon the ring 17, the periphery of the ring may comprise a suitable surface, such as celluloid, adapted to receive erasable pencil marks, with the result that the typist, instead of reading the numerals, merely looks at the position of the pencil mark relatively to the pointer 19. In 55 some forms of the device the numerals may be entirely omitted. This pencil mark receiving surface is especially useful in making condensed carbon records of bill-heads, especially where the typist makes out such 60 records during one part of the day, but is

likely to be called away between the making of such records.

To use the present invention for this purpose, the typist may insert the short bill-head, together with the long record sheet and 70 the carbon, and write the entries thereon. When making the last entry upon the first bill-head, the typist may make a pencil or other mark at the pointer 19 upon the celluloid surface 24, and then withdraw the bill-head while the record sheet and carbon sheet remain in the machine. Then the typist may insert the next bill-head, clamp it to the platen by casting on the feed-rolls, which were cast off to remove the first bill-head, 75 and rotate the platen as many line-spaces as it is desired to separate the entries from each other. The pencil mark upon the celluloid surface 24 enables the typist to attend to the adjusting of the bill-head, and, if need be, to 80 leave the machine for a while, confident that on coming back the pencil mark will indicate whether the platen has been advanced or not. Thus, the pencil mark saves the typist the need of memorizing, even for a moment, any 85 number displayed upon the scale. This operation can be repeated as many times as is desired, the typist placing pencil marks in as many columns 21, 22, etc., as is convenient. Since such marks are readily erased from 90 celluloid by mere rubbing of the finger or eraser, the celluloid surface may be used for many kinds of work at frequent intervals.

Variations may be resorted to within the scope of the invention, and portions of the 100 improvements may be used without others.

Having thus described my invention, I claim:

1. In a typewriting machine, the combination with a revoluble platen and an axle 105 therefor, a channeled ring fast to said axle, a scale-carrying-ring revoluble upon the first ring, and a rubber body lying within the channel and bearing against the scale ring to yieldingly detain it whenever set. 110

2. In a typewriting machine, the combination with a revoluble platen and an axle therefor, a ring channeled peripherally and fast to the axle, a scale-carrying-ring journaled on the peripheral surface of the first 115 ring, and a rubber body occupying a small part of the channel and adapted to yieldingly detain the scale ring wherever set.

3. In a typewriting machine, the combination with a revoluble platen and a line-space 120 wheel therefor, of a circular scale adapted to be turned relatively to the line-space wheel, numerals upon said scale for each line-space, said numerals running in one direction and being of one color, numerals 125 for each line-space upon said scale in contrasting color and numbered in the opposite direction, and continuing numerals of the first set for a second rotation of the platen into a column adjacent a column for 130

- the first rotation, said second set of numerals also occupying both columns, and the arrangement of numerals being such that any numeral added to a corresponding numeral of the other set makes the same total. 5
4. In a typewriting machine, the combination with a revoluble platen and an axle therefor, of a circular scale adapted to be turned relatively to the line-space wheel, numerals upon said scale for each line-space, said numerals running in one direction and being of one color, numerals for each line-space upon said scale in contrasting color and numbered in the 10 opposite direction, and continuing numerals of the first set for a second rotation of the platen into a column adjacent a column for the first rotation, said second set of numerals also occupying both columns, and 15 the arrangement of numerals being such that any numeral added to a corresponding numeral of the other set makes the same total, and a celluloid surface at each set of numerals, said surface adapted to receive 20 an easily erasable pencil mark. 25
5. In a typewriting machine, the combination with a revoluble platen and an axle therefor, of a scale upon said axle comprising a unitary ring having a plurality of adjacent circumferential columns of numerals progressively numbered in one direction, and a similar number of columns progressively numbered in an opposite direction, said columns being so disposed that the numerals of one column alternate with the numerals of the other column in a circumferential direction, the numerals of the two sets forming pairs all totaling the same amount. 30
- 40 6. In a typewriting machine, the combina-
- tion with a revoluble platen and an axle therefor, of a channeled ring fast to said axle, a scale-carrying ring revoluble upon said first ring, and friction means within the channel and bearing against the scale 45 ring to yieldingly detain the ring wherever set. 50
7. In a typewriting machine, the combination with a revoluble platen and an axle therefor, of a peripherally-channeled finger-wheel fast to said axle, a scale-ring revoluble upon said finger-wheel, and friction means within the channel of the finger-wheel and bearing against the scale-ring to yieldingly detain the scale-ring wherever set. 55
8. In a typewriting machine, the combination with a revoluble platen and an axle therefor, of a scale on said axle comprising a unitary ring having a plurality of adjacent circumferential columns containing a 60 set of numerals progressively ascending in one direction and also containing a second set of numerals progressively ascending in the opposite direction, adjacent numerals of the two sets forming pairs all totaling the 65 same amount. 70
9. In a typewriting machine, the combination with a revoluble platen and an axle therefor, of a scale on said axle comprising a unitary ring having a plurality of adjacent circumferential columns containing a set of numerals progressively ascending in one direction and also containing a second set of numerals progressively ascending in the opposite direction.
